UNITED STATES PATENT OFFICE.

MAX E. DORSCH, OF CHICAGO, ILLINOIS.

DESIGN FOR AN ANIMAL-TRAP.

• 57,320.

Specification for Design.

Patented Mar. 15, 1921.

Application filed December 1, 1919. Serial No. 341,817. Term of patent 14 years.

To all whom it may concern:

Be it known that I, MAX E. DORSCH, a citizen of the United States, residing at Chicago, in the county of Cook, State of Illinois, have invented a new, original, and ornamental Design for an Animal-Trap, of which the following is a specification, reference being had to the accompanying draw-

ing, in which a perspective view of the design is shown.

I claim:

The ornamental design for an animal trap as shown.

In testimony whereof I affix my signature.

MAX E. DORSCH.
